Attorney

UNITED STATES PATENT OFFICE.

LEONARD ERIKSON, OF MALDEN, MASSACHUSETTS.

LAMP-SOCKET.

SPECIFICATION forming part of Letters Patent No. 738,717, dated September 8, 1903.

Original application filed July 2, 1902, Serial No. 114,104. Divided and this application filed December 12, 1902. Serial No. 134,932. (No model.)

To all whom it may concern:

Be it known that I, LEONARD ERIKSON, a citizen of the United States, residing at Malden, in the county of Middlesex and State of Massachusetts, have invented certain new and useful Improvements in Lamp-Sockets; and I do hereby declare the following to be a full, clear, and exact description of the invention, such as will enable others skilled in the art to which it appertains to make and use the same.

This invention relates to sockets of insulating material for holding incandescent lamps in position; and it consists in the novel construction and combination of the parts, hereinafter fully described and claimed.

In the drawings, Figure 1 is a front view of the lamps and their socket. Fig. 2 is a rear view of the socket, drawn to a larger scale. Fig. 3 is a cross-section taken on line xx in Fig. 2. Fig. 4 is a longitudinal section through the socket. Fig. 5 is an end view of the socket.

A is a trough-shaped reflector of sheet metal and B is a lamp-socket of insulating material secured in the trough of the reflector in any approved manner. The socket B has a cylindrical chamber b at each end, in which is secured a screw-threaded tube b', of thin sheet metal. An incandescent lamp C, of any approved make, is screwed into the tube b' at each end of the socket.

The socket B has two recesses d and e at its middle part, and d' and e' are two metallic bridge-pieces arranged in these recesses, respectively. The bridge-piece d' is arranged on the axis of the lamps and the tube b' and is connected to the central terminals of the lamps by screws f and g, which engage with the end portions of the bridge-piece d'. The bridge-piece e' is arranged to one side of the axis of the lamps and is connected to their other terminals by screws i and j. The heads of these screws bear on flanged end portions of the tubes b' and hold them in position, and their point ends engage with the end portions of the bridge-piece e'. Thin plates of insulating material k, such as mica, are placed over the heads of the screws i and j and are held in position by the central screws f and g.

The line-wires m and m' are connected to the bridge-pieces d' and e' by binding-screws.

The two recesses d and e have a shallow recess n, formed in the socket B around them, and n' is a curved plate of insulating material arranged in the recess n between the bridge-pieces and the metallic reflector. 55

I do not herein broadly claim the combination of the socket with the reflector and the means for connecting these parts together, as the same is claimed in a separate application filed July 2, 1902, Serial No. 114,104, from 60 which the subject-matter of this application has been divided.

What I claim is—

1. The combination, with a trough-shaped reflector, of a socket of insulating material 65 secured in the said reflector and provided with two recesses at its middle part and a shallow recess surrounding them, lamps carried by the said block, metallic bridge-pieces arranged in the said recesses and connected in circuit with the said lamps, and a plate of insulating material arranged in the said shallow recess between the bridge-piece and the reflector, substantially as set forth.

2. The combination, with a socket of insulating material having a chamber at one end and two recesses in one side, of a metallic tube for engaging with the lamp arranged in the said chamber, metallic bridge-pieces for the line-wires to connect with arranged in the said 75 recesses, a screw which holds the said tube in position and engages with one of the said bridge-pieces, and a contact-screw arranged on the axis of the said tube and engaging with the other said bridge-piece, substantially as 80 set forth.

3. The combination, with a socket of insulating material having a chamber for engaging with a lamp at each end and two recesses at its middle part, of metallic bridge-pieces 90 for the line-wires to connect with arranged in the said recesses and arranged out of line with each other, and contact-screws inserted through the said chambers and engaging with the said bridge-pieces, substantially as set 95 forth.

4. The combination, with a socket of insulating material having a chamber at one end, of a metallic tube for engaging with the lamp arranged in the said chamber, metallic bridge- 100

pieces for the line-wires to connect with arranged out of line with each other, a screw which holds the said tube in position and engages with one of the said bridge-pieces, a 5 plate of insulating material arranged in the said tube over the head of the said screw, and a contact-screw passing through the said plate and arranged at the axis of the said tube and

engaging with the other said bridge-piece, substantially as set forth. 10

In testimony whereof I affix my signature in presence of two witnesses.

LEONARD ERIKSON.
